MATERIAL WORKING APPARATUS

Daniel Vaughn Waters, Flemington, N. J., assignor to Western Electric Company, Incorporated, New York, N. Y., a corporation of New York

Application March 31, 1944, Serial No. 529,009

4 Claims. (Cl. 90—18)

1

This invention relates to material working apparatus, and more particularly to apparatus for pointing terminals of vacuum tubes.

There are various types of vacuum tubes many of which contain terminals of pin-like structures projecting from the bases thereof for forming electrical connections of the various elements of the tubes, through jacks or sockets, with the electrical circuits in which they are to be employed. It is advantageous that the ends of the terminals be rounded or pointed so that their connections with the sockets or jacks, in which they are to be disposed, may be readily made.

An object of the invention is to provide a material working apparatus which is simple in structure, readily operable, and highly efficient particularly in pointing terminals of vacuum tubes.

With this and other objects in view, the invention comprises a material working apparatus having an apertured member for receiving the terminals of a vacuum tube and for guiding the terminals into engagement with rotatable pointing elements adapted to point the terminals.

Other objects and advantages will be apparent from the following detailed description when considered in conjunction with the accompanying drawings, wherein

Fig. 1 is a fragmentary, longitudinal, sectional view of the apparatus;

Fig. 2 is an end elevational view taken along the line 2—2 of Fig. 1;

Fig. 3 is a vertical sectional view taken along the line 3—3 of Fig. 1;

Fig. 4 is an enlarged fragmentary detailed view of one of the pointing elements, and

Fig. 5 is a vertical sectional view taken along the line 5—5 of Fig. 4.

Referring now to the drawings, the apparatus includes a base 10 supporting a motor 11 which constitutes the power means for driving pointing elements 12. The pointing elements 12 are disposed in the substantially conical arrangement shown, supported at spaced positions in apertures of oil impregnated bearing members 14, 15 and 16. These bearing members are supported by brackets 17, 18 and 19, respectively, and are mounted upon the base 10, apertures 20 and 21 being formed in the brackets 17 and 18 to allow for the pointing elements to extend therethrough.

A shaft 25, of the motor 11, has a coupling 26 mounted thereon, the latter having a knurled or roughened portion 27 for fixedly supporting a resilient driving element 28. The element 28 is formed of a commercially known rubber com-

2

position and is adapted for frictional driving connection with metallic rollers 30 which are fixedly mounted upon adjacent ends of the pointing elements 12. Collars 31, fixedly mounted upon the

pointing elements 12 at the opposite side of the bearing member 16 from the rollers 30, cooperate with the latter in maintaining the pointing elements, particularly their material working ends, at desired locations with respect to each other. A reduced or smooth surfaced portion 33, integral with the roughened portion 27 of the coupling 26, is journaled in a bearing aperture of the bearing member 16, to assist in supporting the driving element 28.

An article locating member 35, of the contour illustrated in Figs. 1 and 2, has a lateral portion 36 integral therewith and provided with a tongue portion 37 movable in a groove 38 of the base 10 for adjustment of the member relative to the base and to the working ends of the elements 12. Screws 39, disposed in elongate apertures 40 of the portion 36 and threaded receivable in apertures 41 of the base 10, serve to secure the member 35 at a selected position. The location of the

member 35, with respect to the material working ends of the elements 12, may be further varied through the aid of an adjusting screw 43 which is disposed in a threaded aperture 44 of the member 35, positioned to engage the bracket 17 and locked in any desired position in the member 35 by the aid of a nut 45. Spaced supporting pins 48, mounted upon the member 35 and projecting outwardly in parallel spaced positions therefrom, serve to support an article, namely a vacuum tube

50, terminals 51 of which are to be pointed. A series of apertures 52, depending upon the arrangement of the terminals 51 in the vacuum tube, is formed in the member 35 to receive the terminals and to guide them into the ends of their

respective pointing elements 12. In actual structure the vacuum tube illustrated is not much larger in size than that illustrated in Fig. 1. For the purpose of illustration, the tube from the end of the tip to the finished ends of the terminals is

45 approximately one and three-quarters inches (1 $\frac{3}{4}$ "). Furthermore, the terminals are approximately one-eighth of an inch ($\frac{1}{8}$ ") between centers excepting at the bottom (Fig. 2). This is mentioned to emphasize the difficulty in solving

50 the problem of forming or pointing the closely positioned terminals of the electrical unit, namely, the vacuum tube. Thus it is essential to provide the pointing elements 12 within structures capable of engaging the small and closely positioned terminals simultaneously. Added to this

is the problem of simultaneously driving the pointing elements in like directions. For this reason the elements 12 are of considerable length, it being necessary that they be fanned out slightly so that their rollers 30 may be positioned around and in engagement with the resilient driving element 28.

The pointing elements 12 are identical in structure and a description of the material working end of one will apply to each of the other elements. Attention is now directed to Figs. 4 and 5, illustrating this structure. Here the end of the element 12 shown is notched, as at 54, to receive a cutting blade 55 of the contour shown, particularly in Fig. 4. A pin 56, extending through aligned apertures of the element upon both sides of the notch and through the cutting blade 55, holds the latter in place. It will be observed that recesses 57 and 58 are formed in the end portions of the element 12 conforming to the contour which is to be given the terminal 51 as a result of the cutting edges 59 and 60 of the blade 55. Furthermore, the notch 54 is disposed off center so that the cutting edges 59 and 60 of the cutting blade will lie at the center line of the element.

During the operation of the apparatus, through the energization of the motor 11 driving the element 28 in one direction, the pointing elements 12, through the driving connection of the rollers 30 with the element 28, will be simultaneously driven in like directions, their material working ends being disposed at spaced positions similar to the spacing of the terminals of the vacuum tube 50. Therefore, by placing the vacuum tube so that it will rest upon the supporting pins 48, with the terminals 51 thereof extending into the apertures 52, these terminals may be directed toward their respective pointing elements. By continuing the movement of the article or vacuum tube longitudinally on its supporting pins, the terminals may be simultaneously pointed by the cutting of the ends thereof to the contours illustrated at 65 (Fig. 4). The pointing operation will terminate when the base of the vacuum tube engages the forward surface of the member 35. Furthermore, the terminals will be of like lengths, which may be varied by varying the position of the member 35 with respect to the bracket 17 or with respect to the working ends of the elements 12. A housing, preferably formed of a suitable transparent material and indicated at 66, may be disposed over the major portion of the apparatus as illustrated in Figs. 1, 2 and 3, resting upon the base 10 and secured thereto by suitable means such as screws 67.

Although specific improvements of the invention have been shown and described, it will be understood that they are but illustrative and that various modifications may be made therein without departing from the scope and spirit of this invention as defined by the appended claims.

What is claimed is:

1. A material working apparatus for pointing the outer ends of spaced projections of an article, the apparatus comprising a plurality of elongate elements having work pointing ends disposed at spaced positions comparable with the relative positions of the projections on the article, driven members mounted on the other ends

of the elements, driving means operatively connected to all of the driven members to cause simultaneous rotation of the elements, and means to guide the projections and thus guide the outer ends thereof to the work pointing ends of their respective elements.

2. A material working apparatus for pointing the outer ends of spaced projections of an article, the apparatus comprising rotatable pointing elements disposed at like spaced positions comparable with the relative positions of the projections on the article and having cutting blades mounted in recessed ends of the elements to cut the ends of the projections to form points thereon, means to rotate the elements to cause the cutting blades thereof to point the outer ends of the projections, means to guide the projections and thus guide the outer ends thereof to their respective elements, and means to support the article for movement relative to the guide means and the elements.

3. A material working apparatus for pointing the outer ends of spaced pin-like projections of an article, the apparatus comprising rotatable pointing elements disposed at like spaced positions comparable with the relative positions of the projections on the article, means to rotate the elements to cause pointing of the projections, a guide member for individually guiding the outer ends of the projections toward their respective elements, and means to vary the relative positions of the guide member and elements to vary the final lengths of the projections when pointed.

4. An apparatus for pointing the outer ends of terminals of an electrical unit, which project from the unit in substantially parallel lines and are disposed at spaced positions in a substantially circular group at one end of the unit, the apparatus comprising pointing elements in the form of elongate shafts having like ends recessed and including cutting blades to point their respective terminals, means to rotatably support the pointing elements whereby the recessed ends will be positioned to receive their respective terminals, means to drive the pointing elements simultaneously, and a guide having apertures aligned with the recessed ends of the pointing elements to guide their respective terminals toward and into the recessed ends of the pointing elements.
